UNITED STATES PATENT OFFICE.

HANS E. GRABAU, OF LONG ISLAND CITY, NEW YORK, ASSIGNOR TO GABRIEL ABRAHAM, OF NEW YORK, N. Y.

GARMENT-SUPPORTER.

1,239,683.

Specification of Letters Patent. Patented Sept. 11, 1917.

Application filed October 4, 1916. Serial No. 123,686.

To all whom it may concern:

Be it known that I, HANS E. GRABAU, a citizen of the United States, and resident of Long Island City, Queens county, State of New York, have invented a new and useful Improvement in Garment-Supporters, of which the following is a specification.

The invention relates to garment clasps and more particularly to clasps used in connection with hose supporters or garters. The objects of the invention are to provide such a clasp that may be easily manufactured from a flexible non-metallic material such as celluloid; to provide a structure which is specially adapted to be made from a flexible non-metallic material such as celluloid, the device being so arranged that the parts will be sufficiently strong although made of such material; to provide an exceedingly simple and yet efficient clasp and generally to improve this type of clasp. Other objects will appear from the description taken in connection with the drawing, in which:—

25 Figure 1 is a perspective view of the clasp in operative connection with the garment and the other parts of the supporter;

Fig. 2 is a plan view of one member of the clasp;

30 Fig. 3 is a plan view of the other member of the clasp;

Fig. 4 is a side elevation of the latter member;

Fig. 5 is a central cross sectional view 35 showing the clasp members in assembled position and showing the arrangement of the cloth of the garment in dotted lines;

Fig. 6 is a view similar to Fig. 4 and showing another form of the button or tab 40 member.

As clearly shown in the drawings, the usual limb encircling member 10 has its ends connected by means of the ring 11. A tape 12 is secured to this ring and has mounted thereon the two members 13 and 14 of the clasp. As clearly shown in Fig. 2, one member of the clasp consists of a flat piece of sheet material having a rectangular aperture 16 at one end through which the tape 12 45 is adapted to be inserted. A longitudinal slot 18 is formed in this member and has an enlarged end 17 adjacent the aperture 16. The other member 14 of the clasp has a slot 19 at one end corresponding to the 50 aperture 16 in the member 13. At the end 55

opposite the slot 19 a button or tab 20 is arranged parallel and slightly spaced from the body portion of the member. This tab or button 20 is connected to the body portion by means of two reversely arranged 180° bends 21 and 22. As shown in Fig. 4, a small spacing piece 23 may be inserted between the button and the central portion of the neck to act as a reinforcing or supporting member for the button. As shown in Fig. 6 the S-shaped neck which joins the button and the body portion instead of being in the form of Fig. 4 with the spacing block 23 embodied therein may be arranged with one sharp bend 22'. By this arrangement the tab or button extends along one side of the bend 21' and a contact therebetween gives the same reinforcing action as the spacing piece 23 in Fig. 4. It will be noted that in both of these forms that the 70 button is joined to the body portion by a double or S bend, the only difference being that in Fig. 6 the two sides of the bend 22' are in contact, whereas in Fig. 4 they are separated and the spacing piece 23 inserted 75 therebetween. It will be observed that because of this S or double bend that the tab is connected to the body portion in a strong but yielding manner. If the tab were connected to the body portion by a neck which 80 extended at right angles to both the tab and body portion, any movement of the tab relative to the body portion would be localized at the two 90° bends and fracture at one of these places would soon occur. With the 85 arrangement herein disclosed any movement of the tab relative to the body is distributed more or less throughout the two bends and consequently no small limited area of the neck is subjected to all of the deformation. 90

This means that the clasp member with the S bend is adapted for long service. This clasp is adapted particularly to be made from a flexible non-metallic material such as celluloid, and as this substance has no 95 great strength it is necessary to construct the device in such a manner that stresses in the material will not be localized and the parts will be reinforced as much as possible. It is obvious that the construction herein disclosed conforms to these requirements. 100

Having thus described the invention, what is claimed and desired to be secured by Letters Patent is:

1. A garment clasp comprising a member 110

- having an aperture formed therein, a coöperating member of flexible sheet material comprising a body portion and a tab, the latter adapted to be inserted through the 5 said aperture, the said tab being arranged substantially parallel to but offset from its body portion and connected to the latter by a neck having two reversely arranged substantially 180° bends therein.
- 10 2. A member of flexible sheet material for a garment clasp comprising a body portion and a tab arranged substantially parallel to but offset from the body portion and connected to the latter by a neck having 15 reversely arranged substantially 180° bends therein and said tab having a portion thereof coöperating with the part of the neck between the two bends, whereby it is reinforced.
3. A flexible member of sheet material for 20 a garment clasp comprising a body portion, a flat tab arranged substantially parallel to but offset from the body portion and connected to the latter by a neck having two reversely arranged substantially 180° bends 25 therein and a spacing member interposed between the tab and the part of the neck between the two bends.
4. A flexible member of sheet material for 30 a garment clasp comprising a body portion, a flat tab offset from said body portion and arranged so that the end of the body portion is opposite the central part of the tab, and a curved neck connecting the said end of the body portion and the edge of the tab which 35 overlaps the body portion.

In testimony whereof I affix my signature.
HANS E. GRABAU.
